UNITED STATES PATENT OFFICE

HANS JORDAN, OF KARLSHORST, BERLIN, GERMANY, ASSIGNOR TO GENERAL ELECTRIC COMPANY, A CORPORATION OF NEW YORK

ELECTRICAL CONDUCTOR

Application filed November 14, 1927; Serial No. 232,992, and in Germany March 30, 1927.

This invention relates to electrical conductors and is particularly applicable to cables for use in telephony.

One form of cable construction consists in assigning four wires to each of a plurality of quads. The four wires comprising each quad are insulated and are twisted about a common axis, various quads being assembled to form a cable. Two wires which lie diametrically opposite to each other in the quad are used for one side circuit, the remaining two wires being used for the other side circuit. The wires of the two side circuits comprise the conductors of a phantom circuit. The wires of any quad may be of the same diameter, yet different quads may have wires of different diameters, if desired. The capacity per unit length of the phantom circuit in this type of construction is so great when compared with the capacity of the side circuits, that even when these circuits are loaded to provide the same transmission loss, the cutoff frequency of the phantom is lower than that of the side circuits, which, of course, is undesirable.

The conductors of any pair may, if desired, be transposed to secure equal and opposite exposure to, for example, any external inductive influence or other forms of interference. By increasing the distance between the conductors of a pair, it is possible to reduce the electro-static capacity and at the same time increase the inductance of these conductors relatively to each other. As is well known in the art, decrease in the capacity, and within certain limits, increase of the mutual induction are greatly beneficial to transmission.

It is one of the objects of this invention to provide a transposition scheme for use in the construction of cable quads which will effect the elimination of any undesirable capacities, not only theoretically, but also practically. It is a well-known fact that an electrically efficient cable quad may, in practice, result in considerable crosstalk disturbances

because of unavoidable manufacturing difficulties encountered in its construction. The chief disadvantage brought about by these manufacturing difficulties result in the accumulation of capacitative effects, which, though individually small in a particular section of the quad are, nevertheless, of like nature and therefore additive throughout a long section of the cable quad. By providing a transposition scheme, it is possible to adequately overcome the resultant capacitative effects tending to introduce cross-talk, the transposition scheme introducing dissimilar relations as much as possible throughout both side circuits comprising the quad.

This invention will be better understood from the detailed description hereinafter following, when read in connection with the accompanying drawing, showing one form of embodiment of the invention, in which Figure 1 shows a transposition scheme employing the principles of this invention, and Figure 2 shows a cross-section of the conductors of the quad provided in Figure 1.

Referring to Figure 1 of the drawing, there are shown four conductors, A, B, C and D, conductors A and B representing one side circuit and conductors C and D representing the other side circuit. Conductors A and B, for example, may run parallel to each other over a section "a". Upon reaching section "b", these wires may be transposed in order that the upper conductor A may assume the lower position while conductor B may assume the upper position. Upon reaching section "c", these conductors may again be transposed so that conductors A and B may assume the same relative positions as in sections "a". At section "d", another transposition is effected, the conductors A and B assuming the positions present in section "b". These conductors may remain in this relative position throughout a long section of the cable and are then transposed again at section "e". These wires may be transposed periodically

throughout the cable as shown in the drawing. The second side circuit comprising conductors C and B may be similarly transposed throughout its length, transpositions occurring at regular intervals, substantially the same as is the case of the upper side circuit of conductors A and B.

It is apparent that the transposition sections within each of the side circuits are not of the same length throughout. There is a 10 succession of a number of short transposition sections interrupted at regular intervals by a longer transposition section. The transposition scheme of this arrangement is such that 15 a number of short sections are provided, which are interrupted periodically by a longer section, these conditions existing in both side circuits to the same extent. However, the conductors of the quad are so arranged 20 that the series of the short transposition sections in one side circuit are adjacent to one of the longer transposition sections in the other side circuit, and vice versa. The length of the long transposition section may be determined 25 from the expression $W(n+2)$, where W is the length of each small transposition section and n represents the number of serial short sections. In such an arrangement, the couplings introduced in two successive sections, which may be in the same or 30 in different side circuits, substantially balance each other.

In accordance with this invention, the 35 number of short successive transposition sections is to be selected so that the component conductors may assume as many combinations of different positions as possible in both side circuits. In the arrangement shown in Figure 1, three transpositions occur in each 40 side circuit in regular succession and then another occurs after a long interval. Moreover, in the arrangement shown, the conductors of each side circuit are uncrossed, then transposed 180 degrees in a clockwise direction 45 and then transposed 180 degrees in a counterclockwise direction, and so on. Assuming each interval to be composed of two short sections and one long section, O representing an uncrossed section, R a section 50 transposed in a clockwise direction and L a section transposed in counterclockwise direction, then the following positions will be 55 present throughout a definite length of one of the side circuits, these positions being repeated in regular order:

O short	R short	O long
L short	O short	R long
O short	L short	O long
60 R short	O short	L long

The same positions will be present in the second side circuit and similarly repeated in that circuit. Such an arrangement exhibits 65 positive and negative effects in the individual

sections resulting in a multiplicity of mutual positions of the conductors.

Figure 2 shows a cross-sectional view of the conductors. Here A and B represent the insulated conductors of one side circuit and C and D represent the insulated conductors of the other side circuit. It is to be noted that the conductors of each side circuit are adjacent to each other in the quad. Such an arrangement is distinctly different from the arrangement of conductors in the well-known form of star quadded cable in which diagonally opposite conductors form the respective side circuits.

It is to be noted that it is one of the features of this invention to employ point-like transpositions, a point-like transposition being one in which the wires are transposed throughout an extremely small distance as compared to the distance between two successive transpositions. Thus, the slope of the wires at each transposition is very steep.

While this invention has been shown and described in a certain particular embodiment merely for the purpose of illustration, it will be clearly understood that the general principles of this invention may be applied to other and widely varied organizations without departing from the spirit of the invention and the scope of the appended claims.

What I claim as new and desire to secure by Letters Patent of the United States, is:

1. In a cable for telephone systems and the like, the combination of two pairs of suitably insulated conductors, the conductors of each section of one pair being sharply crossed a predetermined number of times at substantially equal intervals and sharply crossed alternately at one longer interval, the one longer interval of each section of one pair being opposite to the serial intervals of each section of the other pair, and conversely, the shorter serial intervals of each section of the first pair being opposite to the one longer interval of each section of the second pair, the conductors of said pairs being twisted uniformly about a common axis, each pair of conductors being employed for the transmission of a telephone conversation.

2. In a cable for telephone systems and the like, the combination of one pair of conductors covered with suitable insulation, the conductors of each pair being divided into sections in each of which said conductors are sharply crossed serially a definite number of times at equal distances and sharply crossed alternately once over a different distance longer than the distance between the serial crossings, a second pair of conductors similarly insulated and similarly crossed, all of said conductors being twisted about a common axis, the longer interval of each section of one pair being placed opposite to the short serial intervals of each section of the other pair, and vice versa.

3. In a cable for telephone and like systems, the combination of four conductors twisted in common about an axis, each section of two adjacent conductors being sharply crossed successively a definite number of times at equal intervals and sharply crossed alternately at one longer and predetermined interval, the short successive intervals of each section of one pair of conductors being adjacent to the one longer interval of each section of the other pair of conductors.

In witness whereof, I have hereunto set my hand this 25th day of October, 1927.

HANS JORDAN.
